UNITED STATES PATENT OFFICE

155,785

DESIGN FOR A COMBINED BABY STROLLER AND PACKAGE CARRIER

Donavon Davis, West Allis, Wis.

Application August 25, 1948, Serial No. 148,285

Term of patent 7 years

(Cl. D14—14)

To all whom it may concern:

Be it known that I, Donavon Davis, a citizen of the United States, residing at West Allis, in the county of Milwaukee and State of Wisconsin, have invented a new, original, and ornamental Design for a Combined Baby Stroller and Package Carrier, of which the following is a specification, reference being had to the accompanying drawing, forming part thereof.

Figure 1 is a front perspective view of a combined baby stroller and package carrier, showing my new design, and

I claim:

The ornamental design for a combined baby stroller and package carrier, as shown.
DONAVON DAVIS.
